[57] CLAIM

The ornamental design for a packaging container, substantially as shown and described.

DESCRIPTION

FIG. 1 is a perspective view of a packaging container showing our new design;

FIG. 2 is an end view thereof, the opposite end being the same in appearance as the end shown;

FIG. 3 is another perspective view showing the bottom thereof; and

FIG. 4 is a top plan view.

*Fig. 1**Fig. 2**Fig. 3**Fig. 4*
